DESIGN FOR A CHILD'S COAT

Ely Klepper, New York, N. Y.

Application August 23, 1939, Serial No. 86,841

Term of patent 3½ years

To all whom it may concern:

Be it known that I, Ely Klepper, a citizen of the United States and residing in Manhattan, in the city, county, and State of New York, have invented a new, original, and ornamental Design for a Child's Coat, of which the following is a specification, reference being had to the accompanying drawing, forming part thereof, wherein

Fig. 1 is a front view of a child's coat showing my new design.

Fig. 2 is a rear view thereof.

I claim:

The ornamental design for a child's coat, substantially as shown.

ELY KLEPPER.
